(57) **CLAIM**

The ornamental design for a display panel with animated graphical user interface as shown and described.

DESCRIPTION

The patent or application file contains at least one drawing executed in color. Copies of this patent or patent application publication with color drawing(s) will be provided by the Office upon request and payment of the necessary fee.

1. Display panel with animated graphical user interface

1.1 is a front view of a first image in a sequence for a display panel with animated graphical user interface;

1.2 is a second image thereof;

1.3 is a third image thereof;

1.4 is a fourth image thereof; and

1.5 is a fifth image thereof.

The outermost broken line rectangle shows the display panel, and forms no part of the claimed design. All other broken lines show portions of the graphical user interface that form no part of the claimed design. The appearance of the transitional image sequentially transitions between the images shown in Reproductions 1.1-1.5. The process or period in which one image transitions to another image forms no part of the claimed design.
